UNITED STATES PATENT OFFICE.

WILLIAM H. SANDERS, OF WINNSBORO, SOUTH CAROLINA.

THREAD GUIDE.

Application filed July 12, 1923. Serial No. 651,079.

To all whom it may concern:

Be it known that I, WILLIAM H. SANDERS, a citizen of the United States, residing at Winnsboro, in the county of Fairfield and 5 State of South Carolina, have invented new and useful Improvements in Thread Guides, of which the following is a specification.

This invention relates to thread guides for use in spinning and twisting machines 10 and has as its objects to provide a guide which will offer a minimum of frictional resistance to the passage of the thread therethrough; to afford a construction which will permit the guide to be readily threaded; 15 to permit the ready replacement of the anti-friction device, which, in the present instance, is a roller; to insure the retention of the thread in the guide and, at the same time, to prevent lateral movement or shifting 20 of the thread on the face of the roller without offering any substantial frictional resistance to the passage of the thread; and, in general, to afford a construction which may be cheaply produced and assembled and 25 which, at the same time, will permit the thread to pass freely and smoothly without liability to chafe and cut the same.

In the accompanying drawings there is shown a preferred and practical embodiment of the invention, and in these drawings:

Fig. 1 is an elevational view, or a view showing the guide in bottom plan as it would be positioned over the spindle of a 35 spinning machine.

Fig. 2 is a side elevational view,

Fig. 3 is a sectional view on the line 3—3 of Fig. 1, and

Fig. 4 is a view of the blank from which 40 the guide is formed.

Referring to the drawings for a more detailed description, the guide is preferably formed from a single piece of metal, such as the blank shown in Fig. 4. It comprises 45 a shank 10 which may be attached to the finger piece of a spinning machine frame. The shank merges into an intermediate connecting portion 11 which, at 12, is bent laterally from the shank but the major portion 50 thereof extends forwardly in the same di-

rection as the shank. The intermediate or connecting portion 11 of the blank serves to connect the shank with the body portion 13, which is longitudinally cut, as indicated at 14, to provide a finger 15 which may be bent from the body portion, as indicated in Figs. 1 and 2. The remainder of the body portion is bent laterally at 16 in the opposite direction from the bend 12 where the shank joins the intermediate portion 11 forming a top 17 for a loop. The body portion is bent downwardly at 18 to form a loop side 19 substantially paralleling the shank and intermediate portion, and is again bent at 20 to form a loop bottom 21. The end 22 of the body portion is bent at 23 so that the end extends upwardly toward the top 17 of the loop and parallels the connecting or intermediate portion 11.

It will be noted that the end portion 22 is 70 slightly spaced from the connecting portion 11 to provide a thread passage or throat 25 having an enlarged inlet or mouth 26. This passage directs the thread within the loop over the tip 27 of the end portion 22.

Within the loop, and preferably spanning or extending across the same there is provided an anti-friction device which, in the preferred form of the invention, is a roller 29 having a bearing in an opening 30 formed 75 in the end portion 22 and in an opening 31 formed in the loop side 19. The opening 30 is of sufficient size to receive a pintle or axle 32 formed integrally with the roller, and the opening 31 is slightly larger to permit the

roller to be inserted through the same into the loop. The opening 31 is countersunk at 33 and is internally threaded to receive a bearing cap 34 having an opening 35 which serves as a bearing for the integral axle 32 and, at the same time, serves to retain the roller in position. Obviously, the invention is not limited to this precise means for retaining the roller within the loop, nor need the pintle 32 be formed integrally with the roller; a separate axle extending through the roller would ordinarily be found satisfactory.

Referring to the construction of the anti-friction roller, it will be noted that the same has a central portion 36 of reduced diameter 100

and adjoining tapering end portions 37 which increase in diameter toward the ends of the roller. The thread within the loop normally passes over the central portion 36 of the roller, the roller rotating to prevent the chafing or cutting of the thread. When the thread moves laterally it engages the end portions 37, and due to the fact that these ends are tapered they prevent lateral shifting movement of the thread by offering a gradually increasing resistance to this movement, which prevents the breaking of the threads.

It is, of course, old and well known in the art to provide grooved pulleys or rollers in thread guides, but I have found that when the thread is confined to narrow grooves it tends to frictionally engage the sides of the groove which, ordinarily being substantially at a right angle to the base of the groove, offer very substantial frictional resistance to the passage of the thread and tend to chafe and cause breakage of the same. Instead of providing a roller having a peripheral groove with sides serving to prevent lateral movement, I accomplish the same result by the reduced central portion 26 and gradually tapering end portions 37, which offer resistance to the thread, and this resistance gradually increases as the thread moves toward the ends of the roller without substantial friction, thereby reducing the breakage of the thread.

The roller may be of any suitable material; such as fiber glass or wood, and it will be noted that the same may be readily replaced, when worn, by simply removing the bearing cap 34, which has a slot 34' which may be engaged by a screw driver or any other suitable implement.

In the use of a thread guide constructed as disclosed it has been found that upon picking up the thread end from the bobbin and traveller, after breakage of thread, any attempt to join same with the broken end of thread near the usual top roller of the machine, causes the guide to automatically thread itself, the passage 11 in the latter, in connection with the movement of the traveller, immediately directing the thread upon the roller 29. The substantially wide roller permits a certain amount of sidewise shifting of threads, and the tapering ends limit the shifting movement but do not strain or chafe very fragile threads which are being twisted. The guide may be stamped or forged from malleable iron, or sheet metal in a single blank, and then subjected to the bending process. The roller bearings may be drilled simultaneously with the forging, or in one operation.

It should be understood that such modifications may be made in the structure illustrated and described without departing from the scope of the invention.

I claim:

1. A thread guide formed from a single piece of metal and comprising a shank, a body portion bent laterally, then over the blank and inwardly to form a loop, said body portion having openings therein to form bearings for an anti-friction roller, an anti-friction roller in said loop, and a connecting portion of said blank joining the shank with said body portion. 75

2. A thread guide formed from a single piece of metal and comprising a shank, a body portion bent laterally, then over the blank and inwardly to form a loop, said body portion having openings therein to 80 form bearings for an anti-friction roller, the end of said body portion being bent within the loop toward the top thereof and having one of said openings therein, an anti-friction roller in said loop, and an intermediate connecting portion of said blank joining the shank with said body portion, said intermediate portion substantially paralleling the end of the body portion and forming a passage for introducing the 85 thread to said roller. 90

3. A thread guide formed from a single piece of metal and comprising a shank, a body portion bent laterally, then over the blank and inwardly to form a loop, said body portion having openings therein to 95 form bearings for an anti-friction roller, the end of said body portion being bent within the loop toward the top thereof and having one of said openings therein, an anti-friction roller in said loop, and a connecting portion of said blank bent laterally 100 from the shank in the opposite direction from said body portion and joining the shank with said body portion, said intermediate 105 portion substantially paralleling the end of the body portion and forming a passage for introducing the thread to said roller.

4. A thread guide formed from a single blank and comprising a shank, an intermediate connecting portion, and a body portion forming a loop, said body portion being longitudinally slit to form a finger bent laterally therefrom and said loop being formed by bending the remainder of the body portion laterally, then over the intermediate portion and then inwardly, and an anti-friction roller positioned in and extending across said loop. 110 115

5. A thread guide formed from a single blank and comprising a shank, an intermediate connecting portion, and a body portion forming a loop, said body portion being longitudinally slit to form a finger bent laterally therefrom; and said loop being 120 formed by bending the remainder of the body portion laterally, then over the intermediate portion, then inwardly, the end of the body portion then extending upwardly 125 within the loop and substantially parallel- 130

ing said connecting portion, and an anti-friction roller positioned in and extending across said loop.

6. A thread guide formed from a single blank and comprising a shank, an intermediate connecting portion, and a body portion forming a loop, said body portion being longitudinally slit to form a finger bent laterally therefrom and said loop being

formed by bending the remainder of the body portion laterally and then over the intermediate portion, and an anti-friction roller positioned in and extending across said loop.

In testimony whereof I have hereunto set 15 my hand.

WILLIAM H. SANDERS.
